UNITED STATES PATENT OFFICE.

CHARLES J. DYER, OF OAKLAND, CALIFORNIA.

GAME APPARATUS.

1,106,499.

Specification of Letters Patent. Patented Aug. 11, 1914.

Application filed March 25, 1913. Serial No. 756,816.

To all whom it may concern:

Be it known that I, CHARLES J. DYER, citizen of the United States, residing at Oakland, in the county of Alameda and State of California, have invented certain new and useful Improvements in Game Apparatus, of which the following is a specification.

This invention relates to game apparatus. 10 The primary object of the invention is to provide a game apparatus which, to a certain extent, is controlled by chance, yet which is of a construction whereby the player may secure better results by skillful manipulation of the member which controls the movement of the game pieces.

Another object of the invention is to provide a construction in which the results of the manipulation of the game pieces may be 20 quickly and accurately determined.

A still further object of the invention is to provide a construction with but few movable parts thereby preventing the device from being rendered inoperative from improper manipulation or excessive use.

A further object of the invention is to provide a construction which may be economically manufactured and which may be played by inexperienced persons.

30 For a full understanding of the invention, reference is to be had to the following description and accompany drawing, in which:—

Figure 1 is a perspective view; Fig. 2 is a 35 top plan view, the top being removed; Fig. 3 is an end view of the device for manipulating the game pieces; and Fig. 4 is a perspective view of said device.

Corresponding and like parts are referred 40 to in the following description and indicated in all the views of the accompanying drawing by the same reference characters.

In the drawing, 10 designates a substantially rectangular box. A lid 11 is hingedly connected to the end wall 12 of the box, a plurality of pivotally connected links 13 and 14 connecting the lid with the side wall 15 of the box, these members maintaining the lid in raised position. The base 16 of 50 the box is provided with a plurality of openings 17 immediately in front of the end wall 12. These apertures are arranged in rows disposed in spaced relation. Each aperture is designated by a numeral, indicating what 55 may be termed the value of the particular aperture, there being several of the aper-

tures indicated by the same numeral, the numbers preferably ranging from one to six. It will be noted that instead of each aperture having a designating numeral, 60 each of the rows of apertures may be indicated by a numeral, the apertures in said row having the valuation of the designating numeral of the row.

A game piece manipulating device is arranged adjacent the end of the box remote from the apertures. This manipulating device consists of a tray 18 formed with the base 19, the rear wall 20, and the end walls 21. A block 22 is secured to the under face 65 of the base 19 adjacent its front edge. This block supports a resilient rod 23, the rod being preferably attached to the block by means of staples 24. The terminals of the rod project beyond the end walls 21 of the 70 tray and extend through the eyes 25 of securing devices 26 which are arranged in the base 16 of the box. It will be noted that as the tray is pivoted adjacent its front edge that its rear edge 27 will, at all times, rest 75 on the bottom of the box, thus maintaining the tray in a position to receive the game pieces.

The game pieces which are employed are a plurality of spheres 28 of such diameter 80 that they may be seated in the openings 17. The player is allowed a certain number of these game pieces which he places, either singly or as an entirety, within the tray 18. The tray is provided with a button 29 by 85 means of which it may be manipulated. The tray is then tilted and the game pieces projected toward the wall 12. If they are projected with sufficient force to strike the wall 12, they will be returned toward the 90 tray. If they are permitted to merely roll toward the said wall, traversing the path in which the apertures are arranged, certain or all of the game pieces will seat within the 95 openings 17. Batten strips 30 are secured to the base and sides of the box, the batten strips being substantially rectangular in cross section and mitered at the corners to form a snug joint. Particular attention is called to this construction as it provides a 100 sloping wall adjacent the edge of the box which forms a return incline for the game pieces which has a tendency to throw them 105 toward the center of the box.

The object of the game is to seat the balls 110 in apertures designated by a particular number, or in a certain number of apertures,

the valuations of which, when added together, produce a certain number. The lid is provided with numbers which designate the winning sets of numbers and those numbers which have no valuation. The player may, as before stated, project the balls singly from the tilting tray, and in this manner attempt to seat them independently, it being necessary to exercise particular skill in driving the ball toward the apertures in order that it may not merely rebound from the rear wall and roll over the apertures at a speed which will prevent its seating within the same. The peculiar construction and arrangement of the tray is such as to tend to defeat the accurate rolling of the game pieces toward the openings, that is, the player cannot accurately govern the speed of the balls by reason of the angle at which they must necessarily contact with the box.

Particular attention is called to the peculiar manner of mounting the tray. The tray is mounted on the central portion of the resilient rod, which gives the tray a certain amount of resiliency when it is manipulated, thus placing the player at a disadvantage in the accurate manipulation of the balls. It will be noted, therefore, that while a certain degree of skill is necessary to secure the best results, that the element of chance will operate to prevent such skillful manipulation as to permit of all the balls being placed within the apertures with ease. Attention is called to the fact that the peculiar arrangement of the batten strips have a tendency to deflect the game pieces toward the center of the board, and that the game pieces which ride over the batten strips adjacent the apertures in the base of the box will be returned across the apertured surface at a speed which will prevent their being seated in the apertures.

The many advantages of a construction of this character will be clearly apparent, as it will be noted that the device is such as may be easily and economically manufactured, and that the various parts may be readily assembled.

It will also be noted that the structure will not get out of order through improper or excessive manipulation.

What I claim is:

1. A game apparatus comprising a box which includes bottom, side and end walls, 55 openings formed in the bottom of the box adjacent one end and disposed to receive game pieces delivered from the other end of the box, a game piece delivering member supported adjacent the end wall of the box 60 remote from said apertures, and a flexible rod secured to the under face of said delivering member, the terminals of said rod extending through eyes secured to the bottom

of the box, whereby the delivering member may participate in a pivotal movement, the 65 rod intermediate its ends being flexed during said movement.

2. A game apparatus comprising a substantially rectangular box including a bottom, side walls and end walls, the bottom adjacent one of the end walls being provided with apertures, and a game piece delivering member supported adjacent the other end of the box, said member comprising a base, a rear wall and end walls, a block secured 70 to the under face of the base, and a resilient rod extending longitudinally of the base and secured to said block, the terminals of said rod being supported by the base of the box.

3. A game apparatus comprising a substantially rectangular box including a bottom, side walls and end walls, the bottom adjacent one end being provided with a plurality of apertures, a game piece delivering member mounted at the other end of the box, said member comprising a tray which includes a bottom, end walls and one side wall, and a rod secured to the under face of the bottom adjacent one of its edges, said rod being pivotally mounted on the bottom of the box.

4. A game apparatus including a game board, game pieces, a delivering member therefor, and a resilient mounting flexibly supporting said delivering member and arranged upon the board.

5. A game apparatus including a game board, game pieces, an oscillating delivering member therefor, and a resilient pindle arranged on said board and flexibly supporting the delivering member.

6. A game apparatus including a game board, game pieces, an oscillating delivering member therefor, and a resilient mounting for said delivering member arranged on the board whereby the direction of said member may be varied as it is oscillated.

7. A game apparatus including a game board, game pieces, a delivering member therefor, and a resilient mounting for said member arranged on the board, whereby an oscillatory movement may be imparted to said member in a plane parallel with said mounting.

8. A game apparatus including a game board, game pieces, a delivering member therefor, and a resilient rod arranged upon the board and pivotally connected to and serving to yieldably support the delivering member.

In testimony whereof I affix my signature in presence of two witnesses.
